UNITED STATES PATENT OFFICE.

SAMUEL L. POWELL, OF NEWBERRY, SOUTH CAROLINA.

SHUTTER-WORKER.

SPECIFICATION forming part of Letters Patent No. 657,448, dated September 4, 1900.

Application filed July 2, 1900. Serial No. 22,314. (No model.)

To all whom it may concern:

Be it known that I, SAMUEL L. POWELL, a citizen of the United States, residing at Newberry, in the county of Newberry and State of 5 South Carolina, have invented a certain new and useful Improvement in Shutter-Workers, of which the following is a full, clear, and exact description.

This invention relates to that class of shutter-operating mechanisms by which outside shutters or blinds which are hinged to the window casings or frames may be opened and closed and locked in either or any intermediate position by operation of mechanism 15 within the building and without opening the windows.

The invention comprises a band-and-pulley mechanism arranged in part within the building and upon the window sill or casing or 20 frame and coöperating with an arm having a peculiar sliding connection with the shutter for unlocking and opening it and for closing and locking it and for retaining it in any intermediate positions, all as I will proceed now 25 to set forth and finally claim.

In the accompanying drawings, illustrating my invention, in the several figures of which like parts are similarly designated, Figure 1 is a vertical section of part of a window-frame with my shutter-worker and part of the shutter in elevation. Fig. 2 is a top plan view of the inside operating mechanism. Fig. 3 is a front elevation, with parts broken away, of the mechanism shown in Fig. 2. 35 Fig. 4 is a perspective view of the locking-dog. Fig. 5 is a perspective view of the shutter mechanism and part of the arm. Fig. 6 is a vertical section of the outside pulley. Fig. 7 is a top plan view of the stand for the 40 pulley of Fig. 6. Fig. 8 is a vertical section of a modified form of sprocket-wheel which may be substituted for the pulley of Fig. 6. Fig. 9 is a perspective view of a modified form of shutter-fastener.

45 The window-sill *a* and the frame or casing *b* may be of usual construction. On the facing *c* is secured, as by screws, a stand *d*, having a stud-shaft *e*, upon which is mounted to receive a pulley or wheel *f*, adapted to 50 receive a cord, rope, band, or chain *g*, which may be made fast thereto by a pin or pins *h*. This pulley or wheel *f* is provided with a de-

pending handle *i* for rotating it. The stand *d* is provided with bearing-ears *j*, in which are mounted the guide-pulleys *k* on axes at 55 right angles to the axis of the said pulley or wheel *f*, and the cord or other connector *g* passes over these guide-pulleys *k*. The pulley or wheel *f* is made or provided with rack-teeth *l* on its rim, and a dog *m* is pivoted at 60 *m'* to the stand *d* and has a tooth *m''*, which is adapted to engage with the rack *l* to hold the pulley or wheel *f* in any desired position, and said dog is also provided with a knob or handle *m'*, by which its tooth may be released 65 from engagement with the rack-teeth *l*, the said dog otherwise operating by gravity.

Upon the sill *a* is mounted a pulley to receive the cord *g* and to transmit motion to the shutter-operating arm, as I will now proceed 70 to describe. In one form of my invention I provide a stand *n*, (see Figs. 6 and 7 especially for details,) which may be screwed to the sill and is provided with a stud-shaft *n'*, upon which turns the pulley *o*, and this pulley receives the cord *g*. The stand *n* may have a vertical flange *n''* to inclose the perimeter of the pulley *o*, or it may be made without said flange, as indicated in Fig. 8. The pulley or wheel *o* has a grooved or otherwise-constructed perimeter to receive the said cord, band, or chain, or it or the wheel, or both of them, may be made as sprocket-wheels, as indicated in Fig. 8. From the face of the pulley or wheel *o* project forked 80 bearings *p* and *q*, the former being adapted to have pivotally connected therewith and in an adjustable manner the shutter-operating arm *r*, while the forked bearing *q* is of sufficient height to serve as a guide and stay for 85 the said operating-arm in its movement to open and close the shutter. As shown in Fig. 6, if the flange *n''* be employed the pulley or wheel *o* may be rabbeted to overhang said flange, so as to exclude moisture and dust 90 from entrance between the stand and the wheel. The arm *r* has a number of transverse openings *r'* to receive the pin *r''*, by which it is pivoted to the bearing *p*. The outer end of the arm *r* is curved at *r''* and 95 forked at *r''* and provided with a roller *r''*. This forked end of the arm straddles a rail *s*, which is made fast to the shutter horizontally thereof in any suitable way, and its 100

outer end has the crook s' for a purpose presently appearing. A strip of metal t is arranged upon the shutter parallel with the rail s to form a runway or wear-plate for the 5 roller r^5 , and at the end of this strip t is a double inclined lug u , arranged adjacent to the crook s' of the rail s . The shutter-fastener v is also secured to the shutter adjacent to the crook s' , and it has the upwardly-projecting member v' , which extends into the path of movement of the roller r^5 and adjacent to the lug u . Now when the wheel f is rotated and the wheel o is also rotated thereby the arm r is swung inwardly or outwardly 10 to move the shutter. Suppose that the shutter is closed and locked by the fastener v . The first impulse of the movement causes a depression of the roller and of the arm against the extension v' of the fastener, so as to release the fastener from its engagement with the stationary part thereof on the window-sill, and then the said roller mounts the lug u and bears against the strip t and pushes open the 15 shutter to the desired extent. If it be desired to only partly open the shutter and to hold it in such position, the dog m is caused to engage with the rack-teeth l , and this is true of any intermediate position between fully 20 opened and fully closed, and it is also obvious that the shutter may be locked in fully-opened position by the same means. The crook s' affords the necessary room for the play of the bent end of the shutter-operating arm for unlocking the shutter-fastener and 25 in traveling from it over the lug u and upon the strip t .

As shown in Fig. 5, the rail s has independent fastenings at each end; but, as shown in Fig. 9, the plate w of the shutter-fastener 40 may be made with the lugs $w' w'$ to serve the double purpose of lugs as such and for either right or left hand operation and to receive the outer end of the rail s , holes w^2 being provided in these lugs for this purpose.

45 It has been already mentioned that the connecting device g may be secured to the pulley f by pins h , and a similar pin h' may be used to connect it with the pulley o .

One very important feature of the present 50 invention is that the parts may be secured in

position without any other cutting than holes for the passage of the connecting device g from one wheel to the other—that is to say, no recessing of the window sill or frame or of the shutter is required for the application of 55 the parts of my invention.

What I claim is—

1. A shutter-worker, comprising a stand, a pulley mounted thereon, means to rotate said pulley, guide-pulleys mounted upon said stand and at right angles to the axis of the main pulley first mentioned, an outside pulley, a cord, chain, or band connecting the two pulleys, and an arm pivoted to the outside pulley and adapted to be movably connected 60 with the shutter, substantially as described.

2. A shutter-worker, comprising a stand, a pulley mounted thereon, means to rotate said pulley, guide-pulleys mounted upon said stand and at right angles to the axis of the 70 main pulley first mentioned, an outside pulley, having upwardly-projecting forked bearings, an arm pivoted in one of said bearings and guided by the other and adapted to be connected with the shutter, and a power-transmitting connector engaging the pulleys, substantially as described.

3. A stand, a pulley mounted thereon and provided with rack-teeth, a dog for engaging 80 said teeth, means to rotate said pulley, and guide-pulleys arranged on the stand, combined with a stand having an upright flange, a pulley mounted upon said stand within said flange, a cord, chain, or band for connecting said pulleys, and a shutter-operating arm pivoted to the incased pulley, substantially as 85 described.

4. The combination with a shutter-worker having a swinging arm, of a shutter-fastener 90 having a plate provided with oppositely-arranged inclined lugs to coöperate with said swinging arm and adapted for use on right or left hand shutters, substantially as described.

In testimony whereof I have hereunto set my hand this 16th day of June, A. D. 1900. 95

SAMUEL L. POWELL.
